OPERATING MECHANISM FOR ELECTRIC
SWITCHES

George J. Meuer, Milwaukee, Wis., assignor to
Cutler-Hammer, Inc., Milwaukee, Wis., a cor-
poration of Delaware

Application May 15, 1941, Serial No. 393,608

9 Claims. (Cl. 200—17)

This invention relates to improvements in operating mechanisms for electric switches, and more particularly for single switch mechanisms of the double-throw type.

A primary object of the invention is to provide a three-pushbutton type of control for a double-throw switch having an intermediate "off" position.

Another object is to provide a three-pushbutton operating mechanism for a double-throw, three-position switch of well known form.

Another object is to provide an extremely simple and inexpensive pushbutton operating mechanism of the aforementioned character.

Another object is to minimize the number of different parts required to provide pushbutton operating mechanisms having substantially different operative characteristics.

Another object is to provide novel interlocking means to insure against depression of either of two of the three pushbuttons, after depression of another of the same pending momentary depression of the third pushbutton of the mechanism.

Another object is to facilitate elimination of the interlock last mentioned, while at all times enabling utilization of the third pushbutton to effect "off" positioning of the switch parts.

Other objects and advantages of the invention will hereinafter appear.

The accompanying drawing illustrates certain preferred embodiments of the invention which will now be described, it being understood that the embodiments illustrated are susceptible of modification in respect of certain structural details thereof within the scope of the appended claims.

In the drawing,

Figure 1 is a top plan view of a single switch, three pushbutton control station constructed in accordance with my invention.

Fig. 2 is a vertical sectional view, on the line 2—2 of Fig. 1, certain of the switch parts and operating elements being shown in side elevation.

Fig. 3 is a fragmentary vertical sectional view, on the line 3—3 of Fig. 1, the main body portion of the enclosing casing and portions of the sheet metal supporting member being omitted.

Fig. 4 is a fragmentary view similar to Fig. 2, but showing the operating elements in different relative positions.

Fig. 5 is a sectional view, on the line 5—5 of Fig. 3, further illustrating the manner in which each of the three pushbuttons is restrained against relative rotation, and

Fig. 6 is a fragmentary view, partly in side elevation and partly in vertical section, illustrating a slightly modified form of switch operating mechanism constructed in accordance with my invention.

The switch operating mechanisms herein disclosed are functionally similar to those described and claimed in my application, Serial No. 383,667, filed March 17, 1941, but differ from the latter in respect of structural details and in respect of the use thereof in conjunction with a single switch of the double-throw, three-position type. The particular double-throw, three-position switch which I prefer to employ is of the character disclosed and claimed in the application of Alvin W. Krieger, Serial No. 365,907, filed November 16, 1940, to which reference may be had for a more detailed description of the switch parts.

Referring first to the three-pushbutton control station illustrated in Figs. 1 to 5, the numeral 10 (Fig. 2) designates the main body portion of an enclosing casing, which body portion is preferably bent to box-like shape from a single sheet metal blank of suitable form, the inwardly extending flanges 11^a and 12^a on the end walls 11 and 12 of said body portion being rigidly connected with the side walls, one of which is shown at 13, as by spot-welding in the usual manner. Rigidly attached to the end walls 11 and 12, as by riveting, are lugs or brackets 14 and 15 which are respectively provided with tapped openings to receive the shanks of a pair of screws 16, 16, whereby the sheet metal member 17 is removably attached to portion 10, said member 17 acting as a cover for the enclosing casing and as a support for the switch and its operating mechanism.

The double-throw, three-position switch mechanism of the character shown in said Krieger application Serial No. 365,907, comprises essentially a molded insulating base 18 having a substantially rectangular recess 19 formed therein and opening to the upper surface thereof. The switch herein disclosed is preferably of the three-pole, double-throw type, as best illustrated in Figs. 2 and 3. It is to be understood, however, that the number of poles of the particular switch illustrated may be reduced, if desired, or a different double-throw switch having a greater number of poles (not shown) may be employed. Where a multi-pole switch is employed, the barriers (one of which is shown at 20 in Fig. 2) serve to divide the recess 19 into the required number of substantially separate arcing compartments. Within each arcing compartment is a pair of longitudinally spaced stationary end con-

acts 24 and 22 and a contactor 23 which is pivotally supported therebetween, said contactor having upwardly angled arms both of which are disengaged from contacts 24 and 22 in the intermediate or "off" position of the contactor and either of which contacts may be engaged by the contactor upon tilting of the latter to one or the other of its extreme positions. The six stationary contacts 24 and 22 are provided with like terminal plates 23; two of the contactor supports are provided with like terminal members 25; the intermediate contactor support is provided with a terminal member 26 of slightly different form, and all of said terminal plates and terminal members are provided with the usual binding screws, as shown.

The means for effecting intermediate "off" positioning of the contactors 23, or joint movement thereof to their opposite extreme positions respectively, comprises an insulating block 27 carrying three spring-pressed plungers 28 for cooperation with the respective contactors, block 27 being engaged by the forked or notched lower end 29^a of a lever 29 which is pivotally supported by a pin 30 carried by brackets 31, 31 attached to the bulged cover plate 32 which is rigidly secured to the upper surface of base 18, as by means of a pair of metal eyelets 33. As shown, lever 29 is preferably of laminated form.

Lever 29 is provided with a pair of integral oppositely extending arms 29^b and 29^c the enlarged outer end portions of which are provided with substantially circular openings 29^d and 29^e, which are adapted to accommodate pivot pins 34, 34 of relatively smaller size than said openings (see Fig. 2). Pins 34, 34 penetrate openings provided in pairs of lugs 35^a formed integrally with plates 35, 35 which respectively underlie the lower ends of a pair of end pushbuttons 36 and 37, molded from any suitable insulating material. Pushbuttons 36 and 37 are preferably of like form structurally, the same differing only in respect of the legends applied thereto, as indicated at 36^c and 37^c in Fig. 1. As shown at the left hand end of Fig. 2, each pushbutton 36 and 37 is provided with a substantially cylindrical recess 38 and with a hollow substantially cylindrical metal insert 39, whose reduced lower end 39^a is upset over the lower surface of its associated plate 35 to rigidly secure the same to its respective button 36 or 37.

As shown in Figs. 4 and 5 buttons 36 and 37 are provided on the lower surfaces thereof with pairs of studs 36^b, 36^b and 37^b, 37^b molded integrally therewith and closely positioned on opposite sides of a reduced portion of each plate 35 to positively insure against rotary displacement of the respective button relatively thereto.

As best illustrated in Fig. 2, a flat sheet metal plate 40 is superimposed upon the cover plate 32 and is also rigidly secured in position, as by means of the aforementioned eyelets 33, plate 40 having an opening 40^a (Fig. 2) to accommodate the bulge in cover plate 32. Inasmuch as the purpose of plate 40 is primarily to afford a greater area than is provided by the plate 32 (which is standard with a switch of this character), it will be apparent that the result contemplated may likewise be attained by correspondingly increasing the dimensions of plate 32.

As shown, plate 40 has rigidly attached thereto at each end thereof a metal stud 41, as by upsetting the reduced lower end 41^a of the latter over the lower surface of said plate. Studs 41, 41 are surrounded by coiled springs 42, 42 whose upper ends bear at all times under a predeter-

mined degree of compression against the upper end walls of the button recesses 38 aforementioned. As best illustrated in Fig. 2, the studs 41, 41 are of a length to extend within the recesses 5 in the respective buttons in the normal positions thereof corresponding to the "off" position of the switch mechanism, while the recesses 38 are of such height as to provide clearance for said studs upon extreme lower positioning of each 10 button (see the right hand end of Fig. 4). Also, as shown at the left hand end of Fig. 4, in the upper extreme position of either of said buttons the spring 42 will act to insure proper alignment thereof with respect to its associated stud 41 to assist in limiting each of said buttons to reciprocating movement in a straight line.

To further assist in restricting buttons 36 and 37 to straight line reciprocating movements I prefer to provide member 17 with openings to 20 accommodate each button with a fairly close sliding fit, each opening having associated therewith an upstanding peripheral flange 17^a, 17^a, for a similar purpose.

In practice the springs 42, 42 are of sufficient 25 strength individually to effect return of the various parts thus far described to the positions thereof illustrated in Fig. 2 upon manual release of either of the pushbuttons 36 or 37 after depression thereof, it being obvious that the lever 30 29 acts to insure against simultaneous depression of both of said end buttons, whereby all possible strain upon the switch contactors and contacts is prevented. It is likewise obvious that the form 35 of the switch contactors and the operating elements associated therewith (other than the pushbuttons 36 and 37) are such as to inherently prevent engagement of said contactors with the opposite end contacts simultaneously.

However, I prefer to provide means for latching 40 the switch mechanism in either of its extreme "on" positions, and to provide for manual return of the switch mechanism to its intermediate "off" position. For this purpose lever 29 is provided with an upward extension 29^f having an 45 opening or slot 29^g of approximately U-shape formed therein. The third or intermediate pushbutton 43 of the station has formed therein by the molding operation a downwardly opening recess 43^a extending throughout the major portion of the length thereof, the form of said recess in transverse cross section being best illustrated in Fig. 5, and the transverse dimensions thereof being such as to freely accommodate the upright portions of brackets 31, 31 and the enlarged 55 opposite ends of pin 30. The opposed walls of recess 43^a are provided with aligned slots 43^b and 43^c, of somewhat less height than the recess, said slots being adapted to provide clearance for the arms 29^b and 29^c and extension 29^f of lever 29 60 during oscillatory movements of the latter.

Button 43 is further provided with a diagonally 65 arranged pair of downwardly opening auxiliary recesses 43^d and 43^e of relatively small height (as indicated in dotted lines at 43^e in Fig. 3) to accommodate a pair of coiled compression springs 44, 44 whose lower ends are respectively seated upon the horizontal portions of brackets 31, 31. Springs 44 act to bias button 43 upwardly beyond the normal position thereof shown in Fig. 2, but said button is normally restrained against further upward movement by a pin 45 positioned within an opening or passage drilled transversely through said button, said passage having enlarged or countersunk outer ends (as shown in Fig. 3) to

accommodate the head and the upset end of said pin.

As aforesated, the lever 29 is biased by springs 42 to its intermediate position shown in Fig. 2, which position it will assume when button 43 is manually depressed. Upon manual release of button 43 the pin 45 carried thereby will engage the short horizontal edge portion 29^b of slot 29^c, thus limiting the degree of upward movement of said button. Assuming that the right hand end button 37 is thereafter depressed, as shown in Fig. 4, it is obvious that the aforesaid edge portion of the U-shaped slot will move out of restraining relation to pin 45 and the latter will be freed to move upwardly into the left hand end portion 29^b of said slot under the upward bias of springs 44 upon button 43. Such positioning of pin 45 within the left hand end of said slot (Fig. 4) positively restrains lever 29 against counterclockwise movement, thus positively preventing depression of left hand end button 36. However, upon momentary depression of button 43 all of the parts will assume the positions thereof illustrated in Fig. 2, and thereafter either of the end buttons 36 or 37 may be manually depressed individually, and the same will be latched in its depressed position, by the action of pin 45 within one end or the other of slot 29^c.

Thus, with the parts as shown in Fig. 1, it is obvious that upon depression of left hand end button 36 lever 29 will be moved counterclockwise until pin 45 is freed to move upwardly into latching engagement with the right hand end 29^b of slot 29^c, whereupon button 36 will be retained in its depressed position and button 37 will be positively restrained against depression pending momentary depression of button 43.

The support member 17 is provided with an intermediate opening of circular form which is adapted to receive the reduced lower end of a guide tube or flange member 46, said reduced end being spun outwardly over the inner surface of member 17, as shown at 46^a, whereby member 46 acts to insure reciprocating movement of button 43 in a substantially straight line.

The switch mechanism, including the various operating elements thereof aforescribed, is attached to member 17 as by means of four like studs or spacing members 47, whose reduced lower ends (not shown) penetrate correspondingly sized openings in plate 40 and are upset over the lower surface of the latter. The enlarged flat upper ends 47^b of members 47 seat against the inner surface of member 17 and are rigidly attached thereto by spot-welding.

As best illustrated in Fig. 5, the plates 35 extend laterally beyond the pushbuttons 36 and 37 to cooperate with the under surface of member 17, to limit the degree of upward movement of each button, as indicated at the left hand end of Fig. 4.

With reference to Fig. 1, the end buttons 36 and 37 may bear the legends "Slow" and "Fast" and the intermediate button 43 may bear the legend "Stop." Assuming that the pushbutton station is used for control of a two-speed, two-winding, squirrel cage motor on a light duty application, such as a ventilating fan or the like; it is obvious that after depression and latching or locking one of the speed-control buttons (36 or 37) the other of said speed-control buttons cannot be depressed until the intermediate "Stop" button 43 has been momentarily de-

pressed. Also as aforesated this pushbutton station insures against simultaneous closure of the alternative circuits for the controlled motor. The pushbutton station specifically illustrated in Figs. 1 to 5 may be employed as a two-speed across-the-line starter for a three-fourths H. P., A. C. single or polyphase motor at 110 to 230 volts.

In the modification illustrated in Fig. 6, it is to be understood that the switch base (not shown) and the parts located therein or carried thereby may be identical with those illustrated in Figs. 1 to 5. The supporting and operating parts shown in Fig. 6 are also in many respects identical with, or substantially like the corresponding elements aforescribed, the structurally and functionally identical parts or portions of the two devices being given like numerals of reference. Thus the parts 31, 32, 40, 41, 44, 47, 34 and 35 may be identical with those aforescribed. The lever 29^x may be formed from the same blanks as the lever 29 aforescribed, but the upward extension 29^c of lever 29 (and the slot 29^c located therewithin) is preferably omitted from lever 29^x, the portion 29^a, and arms 29^b and 29^c of lever 29^x being the same as those portions of lever 29. It will be understood, of course, that the lever 29 aforescribed might be used, without any change, in the device of Fig. 6, but there is no requirement in the latter device for the aforescribed functions of slot 29^c.

Thus the intermediate or "Stop" button 43^x of Fig. 6 may be produced in the same molding die as the button 43 aforescribed; but the transversely drilled passage of button 43 is omitted from button 43^x, inasmuch as the aforescribed pin 45 is not employed in the device of Fig. 6. Instead, the button 43^x is provided at a predetermined point in its length with a peripheral groove 43^y of semi-cylindrical form in transverse cross section, said groove being preferably formed therein by a milling or grinding operation. A spring ring 48 is forced onto button 43^x and snaps into position within groove 43^y, the open end of ring 48 being positioned as shown in Fig. 6, or at a point 180 degrees removed therefrom. Ring 48 engages the upset end or flange 46^a of tubular member 46 to limit the degree of upward movement of button 43^x, under the bias of springs 44, as aforescribed. The opposite end buttons 36^a and 37^a may be structurally quite similar to the buttons 36 and 37 aforescribed, except that button 36^a preferably is provided at its upper end with the legend "For" (meaning "forward") and button 37^a is provided with the legend "Rev" (meaning "reverse").

The springs 49, 49 associated with buttons 36^a and 37^a are formed of substantially smaller gauge wire (and are consequently of less strength) than the springs 42 aforescribed; the arrangement being such that upon depression of either button 36^a or 37^a the same will be retained in depressed position by the action or bias of the springs associated with the switch contactors, and against the slight upward bias of the respective springs 49. Also as will be obvious from Fig. 6, it is possible to alternately depress the buttons 36^a and 37^a, for circuit commutation, without interference by the "Stop" button 43^x or any of the parts associated with the latter. On the other hand, upon depression of either button 36^a or 37^a the same may be moved upwardly to its normal or circuit interrupting position by momentarily depressing button 43^x, the ring 48 acting under this condition upon one or the other of the arms 29^b (as indicated in Fig. 6) or 29^b to return lever 29^x

to its intermediate or circuit interrupting position. The arrangement disclosed in Fig. 6 affords the advantage of providing for reversing or stopping the controlled motor by plugging, the button 43* being momentarily depressed to effect circuit interruption of the plugged motor in the event that it is desired to completely stop the same. Thus the device of Fig. 6 acts as a reversing across-the-line starter for light duty motors of the rating or capacity mentioned in connection with Figs. 1 to 5.

It will be understood that the legends applied to the several pushbuttons employed may differ from those illustrated, according to the requirements of the particular installation. In like manner the circuit connections to the wiring terminals of the switch may be effected in various different ways to provide for performance of many different electrical functions by either or both of the pushbutton control stations herein disclosed.

I claim:

1. As an article of manufacture, a manually operable switch assembly of the pushbutton type comprising, a flat punched sheet metal supporting member, a unitary double-throw switch mechanism secured to said supporting member, actuating means for said switch mechanism comprising a pair of opposite end pushbuttons and a third pushbutton located therebetween, a pivoted rigid lever having oppositely extending arms to which said end pushbuttons are respectively pivotally connected, a pair of coiled compression springs interposed between the respective end pushbuttons and said supporting member, whereby said end pushbuttons are normally biased toward their upper extreme positions, said lever cooperating with said end pushbuttons to positively prevent simultaneous depression of both of the same, each of said end pushbuttons when depressed being adapted to effect a circuit completing operation of said switch mechanism, associated means common to said end pushbuttons and operable automatically to retain either of the same in its lower extreme position when depressed, said third pushbutton being spring-biased toward its upper extreme position, and said third pushbutton having a part thereof co-operable with said lever and adapted upon temporary depression of the former to effect return of either of said end pushbuttons from its depressed position, to thereby effect circuit interrupting operation of said switch mechanism.

2. In a pushbutton operated single switch mechanism of the double-throw type, in combination, a first pushbutton, a plurality of contacts adapted to be engaged with each other upon depression of said pushbutton to effect completion of an electric circuit, a second pushbutton, a second plurality of contacts, including certain of said first mentioned contacts, adapted to be engaged upon depression of said second pushbutton to effect completion of a different electric circuit, means including a fixedly pivoted rigid lever having a pivotal connection with each of said pushbuttons to positively restrain said pushbuttons against depression thereof simultaneously to thereby insure against completion of both of said electric circuits at one time, means including a coiled compression spring interposed between each of said pushbuttons and a supporting element of said switch mechanism to normally bias the same toward their upper extreme positions, thereby tending to interrupt both of said electric circuits, spring-biased means common to said

pushbuttons to resiliently retain each of the same in its lower extreme position when depressed selectively, either of said first or second pushbuttons when depressed being adapted to effect upward movement of the other of the same, if depressed, against the action of said spring-biased means, to thereby provide for alternate completion of said first and second mentioned circuits individually, and means comprising a third pushbutton having a part engageable with said lever adjacent the point of pivotal support of the latter and adapted when momentarily depressed to effect upward movement of either of said first or second pushbuttons, if depressed, whereby both of said electric circuits are interrupted.

3. In a pushbutton operated single switch mechanism of the double-throw, multi-pole type, in combination, a metal supporting member, a one-piece molded insulating base secured to said supporting member, said base having a recess formed therein and opening to the upper surface thereof, a plurality of stationary contacts arranged at each end of said recess, a plurality of contactors located in said recess and tiltable into and out of engagement with the opposite end contacts respectively, means for effecting tilting movements of said contactors, said means comprising a pivoted lever having oppositely extending arms, a pair of end pushbuttons respectively pivotally connected with said lever arms, said lever acting to positively restrain said pushbuttons against depression thereof simultaneously, for the purpose set forth, a pair of coiled compression springs interposed between said supporting member and the respective pushbuttons to normally bias the latter out of their depressed positions, thereby tending to effect disengagement of said contactors from all of said contacts, a third pushbutton spring-biased toward its upper extreme position, said lever having an approximately U-shaped slot and said last mentioned pushbutton having a transverse pin cooperating with the walls of said slot to positively latch either of said end pushbuttons in its lower extreme position when depressed, said third pushbutton when momentarily depressed effecting movement of said pin relatively to the walls of said slot, whereby the depressed end pushbutton is unlatched to provide for disengagement of said contactors from all of said contacts, and said third pushbutton, said pin and the walls of said slot forming the sole means for effecting release of either of said end pushbuttons when depressed.

4. In a pushbutton operated single switch mechanism, in combination a first pushbutton, a stationary contact, a pivoted contactor movable into engagement with said contact upon depression of said pushbutton to effect completion of an electric circuit, a second pushbutton, a second stationary contact, said contactor being movable into engagement with the latter upon depression of said second pushbutton, means including a pivoted rigid lever having a pivotal connection with each of said pushbuttons to positively restrain the latter against simultaneous depression, to thereby insure against completion of more than one of said circuits at a time, a pair of coiled compression springs respectively associated with said pushbuttons to normally bias the same toward their upper extreme positions, thereby tending to interrupt both of said electric circuits, switch mechanism including spring-biased parts common to said pushbuttons to retain either of the same in its lower extreme position when depressed selectively, against the action of the re-

spective coiled compression springs aforesaid, said last mentioned means including a third pushbutton spring-biased toward its upper extreme position and having a part adapted in such position for latching engagement with said lever, and said third pushbutton being adapted when momentarily depressed to permit the aforementioned normal spring-biased movement of said first or second pushbutton toward its upper extreme position, if depressed, whereby both of said electric circuits are interrupted.

5. In a pushbutton operated single switch mechanism of the double-throw type, in combination, a metal supporting member, a one-piece molded insulating base secured to said supporting member, said base having a recess formed therein and opening to the upper surface thereof, a stationary contact arranged at each end of said recess, a contactor located in said recess and tiltable into and out of engagement with the opposite end contacts selectively, means for effecting tilting movement of said contactor, said means comprising a pivoted lever having oppositely extending arms, a pair of end pushbuttons respectively pivotally connected with said lever arms, said lever acting to positively restrain said pushbuttons against depression thereof simultaneously, for the purpose set forth, a pair of coiled compression springs interposed between said supporting member and the respective pushbuttons to normally bias the latter out of their depressed positions, thereby tending to effect disengagement of said contactor from both of said contacts, a third pushbutton spring-biased toward its upper extreme position, said lever having an approximately U-shaped slot, said last mentioned pushbutton having a recess to accommodate the slotted portion of said lever and a pin extending transversely therethrough for cooperation with the walls of said slot to positively latch either of said end pushbuttons in its lower extreme position, said third pushbutton when momentarily depressed effecting movement of said pin relatively to the walls of said slot, whereby the depressed end pushbutton is unlatched to provide for disengagement of said contactor from both of said contacts, said third pushbutton, said pin and the walls of said slot forming the sole means for effecting release of either of said end pushbuttons when depressed, and means comprising a metal plate rigidly secured to and spaced upwardly from said supporting member, said plate having openings formed therein to accommodate each of said pushbuttons and to assist in restricting the same to reciprocating movement in a straight line.

6. In a pushbutton operated single switch mechanism of the double-throw type, in combination, a metal supporting member, a one-piece molded insulating base secured to said supporting member, said base having a recess formed therein and opening to the upper surface thereof, a stationary contact arranged at each end of said recess, a contactor located in said recess and tiltable into and out of engagement with the opposite end contacts selectively, means for effecting tilting movement of said contactor, said means comprising a pivoted lever having oppositely extending arms, a pair of end pushbuttons respectively pivotally connected with said lever arms, said lever acting to positively restrain said pushbuttons against depression thereof simultaneously, for the purpose set forth, a pair of coiled compression springs interposed between said supporting member and the respective pushbuttons to

normally bias the latter out of their depressed positions, thereby tending to effect disengagement of said contactor from both of said contacts, a third pushbutton spring-biased toward its upper extreme position, said lever having an approximately U-shaped slot, said last mentioned pushbutton having a recess to accommodate the slotted portion of said lever and a pin extending transversely therethrough for cooperation with the walls of said slot to positively latch either of said end pushbuttons in its lower extreme position, said third pushbutton when momentarily depressed effecting movement of said pin relatively to the walls of said slot, whereby the depressed end pushbutton is unlatched to provide for disengagement of said contactor from both of said contacts, said third pushbutton, said pin and the walls of said slot forming the sole means for effecting release of either of said end pushbuttons when depressed, means comprising a metal plate rigidly secured to and spaced upwardly from said supporting member, said plate having openings formed therein to accommodate each of said pushbuttons and to assist in restricting the same to reciprocating movement in a straight line, and a pair of studs rigidly secured to said supporting member and extending upwardly within said springs, said end pushbuttons being recessed to accommodate the upper end portions of said springs and said studs to further assist in restricting the former to reciprocating movement in a straight line.

7. In a pushbutton operated single switch mechanism of the double-throw type, in combination, a metal supporting member, a one-piece molded insulating base secured to said supporting member, said base having a recess formed therein and opening to the upper surface thereof, a stationary contact arranged at each end of said recess, a contactor located in said recess and tiltable into and out of engagement with the opposite end contacts selectively, means for effecting tilting movement of said contactor, said means comprising a pivoted lever having oppositely extending arms, a pair of end pushbuttons respectively pivotally connected with said lever arms, said lever acting to positively restrain said pushbuttons against rotation and against depression thereof simultaneously, for the purpose set forth, a pair of coiled compression springs interposed between said supporting member and the respective pushbuttons to normally bias the latter out of their depressed positions, thereby tending to effect disengagement of said contactor from both of said contacts, a third pushbutton spring-biased toward its upper extreme position, said lever having an approximately U-shaped slot, said last mentioned pushbutton having a recess to accommodate the slotted portion of said lever and a pin extending transversely therethrough for cooperation with the walls of said slot to positively latch either of said end pushbuttons in its lower extreme position, said third pushbutton when momentarily depressed effecting movement of said pin relatively to the walls of said slot, whereby the depressed end pushbutton is unlatched to provide for disengagement of said contactor from both of said contacts, said third pushbutton, said pin and the walls of said slot forming the sole means for effecting release of either of said end pushbuttons when depressed, means comprising a metal plate rigidly secured to and spaced upwardly from said supporting member, said plate having openings formed therein to accommodate each of said pushbuttons and to assist in restricting the same to reciprocating movement in a straight line.

assist in restricting the same to reciprocating movement in a straight line, a pair of studs rigidly secured to said supporting member and extending upwardly within said springs, said end pushbuttons being recessed to accommodate the upper end portions of said springs and said studs to further assist in restricting the former to reciprocating movement in a straight line, said third pushbutton having a kerf formed therein and opening to the lower end thereof, and said lever cooperating with the walls of said kerf to restrain said third pushbutton against rotation and to further assist in limiting the same to reciprocating movement in a straight line.

8. As an article of manufacture, an operating superstructure for an electric switch of the three-position, double-throw type, comprising a metal cover plate, a double-armed lever pivotally supported by said cover plate, a pair of end pushbuttons respectively pivotally and non-rotatably connected with the arms of said lever, a pair of studs rigidly attached to said cover plate, a coiled compression spring surrounding each stud and engaged under compression with each of said pushbuttons, said pushbuttons having recesses to accommodate the upper ends of said springs and said studs to assist in limiting the former to reciprocating movements in a substantially straight line, a third pushbutton slidably associated with said lever and restrained thereby against rotation relatively thereto, means for limiting the degree of upward movement of said third pushbutton, spring means interposed between said cover plate and said third pushbutton to bias the latter toward its upper extreme position, said third pushbutton when depressed being adapted to provide for upward movement of either of said end pushbuttons, if depressed, and a sheet metal supporting member rigidly attached to said cover plate and spaced upwardly from the latter, said sup-

porting member having peripherally flanged openings formed therein to accommodate the respective pushbuttons and to also assist in limiting the same to reciprocating movements in a substantially straight line.

9. As an article of manufacture, an operating superstructure for an electric switch of the three-position, double-throw type, comprising a metal cover plate, a double-armed lever pivotally supported by said cover plate, a pair of end pushbuttons respectively pivotally and non-rotatably connected with the arms of said lever, a pair of studs rigidly attached to said cover plate, a coiled compression spring surrounding each stud and engaged under compression with each of said pushbuttons, said pushbuttons having recesses to accommodate the upper ends of said springs and said studs to assist in limiting the former to reciprocating movements in a substantially straight line, a third pushbutton slidably associated with said lever and restrained thereby against rotation relatively thereto, spring means interposed between said cover plate and said third pushbutton to bias the latter toward its upper extreme position, said lever having a substantially U-shaped slot formed therein, said third pushbutton having a pin extending transversely therethrough for cooperation with the walls of said slot to latch either of said end pushbuttons in its lower extreme position when depressed, each of said coiled compression springs acting to bias its respective end pushbutton toward its upper extreme position, and said third pushbutton when depressed being adapted to effect unlatching of either of said end pushbuttons with consequent movement thereof from its depressed position, said pin also cooperating with the walls of said slot to limit the degree of upward movement of said pushbutton last mentioned.

GEORGE J. MEUER.
